UNITED STATES PATENT OFFICE.

DAVID M. J. WALL, OF BUFFALO, NEW YORK, ASSIGNOR TO LILLIE WALL,
OF SAME PLACE.

DESIGN FOR A BADGE.

SPECIFICATION forming part of Design No. 29,432, dated October 4, 1898.

Application filed July 8, 1896. Serial No. 598,482. Term of patent 7 years.

To all whom it may concern:

Be it known that I, DAVID M. J. WALL, of Buffalo, in the county of Erie and State of New York, have originated and invented a new and useful Design for Campaign-Badges; and I do hereby declare that the following is a full, clear, and exact description thereof, reference being had to the accompanying drawings, forming a part of this specification.

My invention relates to campaign-badges; and it consists of a new and original design which will be hereinafter described and claimed.

In the drawings, Figure 1 is a front elevation of my design, and Fig. 2 is a central longitudinal section of Fig. 1.

Referring to the drawings, the upper part

1 of my design consists of a concavo-convex or shell-shaped body with the upper portion contracted. The intermediate portion 2 is of 20 flat rectangular configuration, and the lower portion 3 is of substantially hollow rectangular configuration and joined to the intermediate portion by a thin wire connection.

I claim—

25 The design for a badge substantially as herein shown and described.

In testimony that I claim the foregoing as my own I affix my signature in presence of two witnesses.

DAVID M. J. WALL.
